United States Patent Office.

P. H. LAWLER AND WILLIAM H. GIBSON, OF ROCHESTER, NEW YORK, ASSIGNEES TO THEMSELVES, G. SHELTON, AND QUINCEY VAN VOORHIS, OF SAME PLACE.

Letters Patent No. 85,104, dated December 22, 1868.

IMPROVED GAS-MACHINE.

The Schedule referred to in these Letters Patent and making part of the same.

To all whom it may concern:

Be it known that we, P. H. LAWLER and WILLIAM H. GIBSON, of Rochester, in the county of Monroe, and State of New York, have invented a new and useful Gas-Machine; and we do hereby declare that the following is a full, clear, and exact description thereof, reference being had to the accompanying drawings, making part of this specification, in which—

Figure 1 is a vertical longitudinal section.

Figure 2 is a vertical transverse section.

The nature of our invention will be understood from the drawings and specifications.

To enable others skilled in the art to make and use our invention, we will describe its construction and operation.

On the inside of a metal case, A, made in any of the known forms of air-carburetting machines, we form a chamber, e, fig. 1, by putting in a partition, a, which is sufficiently high to be above the top of the fluid that may be put in to carburet the air.

At the bottom of the partition there is a small hole, y, fig. 2, to allow the fluid to flow from the main part of the machine to the chamber e, formed by the partition a, so that it will at all times find its level on both sides of the partition.

Inside of this machine we suspend a lever, c. To one end we attach a float, B, that rests on the fluid, and is thereby regulated vertically as the fluid rises and falls. On the other end of the lever c, we pivot a valve, d, which covers the exit-port of the pipe E, leading from the supply-chamber F.

Inside of this machine we suspend an agitator, that is kept in motion by weights or springs. This agitator is formed by placing on the ends of a shaft, h, disks J, which are connected together by several tubes, H, which extend through the disks J.

On one end of the agitator we form a chamber, K, by an extra disk, p, and joining it to the disk on the shaft at their peripheries. The disk p has a circular hole, x², in the centre, sufficiently large to allow the shaft h to pass through, and also the air-supply pipe P, which extends from the outside of the shell forming the machine into the chamber K, and bending upwards near to the point where the spiral tubes enter this chamber.

The object of this invention is to make an air-carburetting machine that will bring the air in contact with the carburetting-liquid, and also of regulating the supply of the liquid from the chamber, where it is held in a more perfect manner than those in use; these two points being the essential parts of those machines.

Its operation is as follows:

The machine may either be filled partially with water and carburetting-fluids, or with the fluid alone, near to the top of the partition a. The float B, resting on the fluid, is caused to rise and fall as it increases or diminishes, and regulates the flow from the supply-chamber, this being necessary, as any over-supply of the fluid causes a waste, and an irregular supply causes a defective light. The air passes into the chamber K from the outside, through the pipe P, and as the agitator is revolved, it passes through the spiral pipes H, into the fluid, thoroughly mixing with it, and then passing off into the gasometer A², on top of the machine.

If the machine is partially filled with water and carburetting-fluid, it is necessary to have small holes, x, at the level of the carburetting-fluid, so that it will be on a level on each side of the partition.

By suspending the regulating-float in the fluid, in a chamber separate from the one in which the agitator works, it is not affected by undulation of the fluid, as it would be if in the same chamber, and therefore operates the valve with a steady motion, as it rises or falls with the fluid.

What we claim as our invention, and desire to secure by Letters Patent, is—

1. The compartment e, in combination with the float B, lever c, valve d, and supply-pipe E, as and for the purpose herein shown and described.

2. The air-supply pipe P, chamber K, and spiral pipe H, all acting conjointly, as and for the purpose shown and described.

P. H. LAWLER.
W. H. GIBSON.
